FUMIGATING DEVICE

Filed April 26, 1927

UNITED STATES PATENT OFFICE.

CAREY CARTER WINCHESTER, OF ATLANTA, GEORGIA, ASSIGNOR TO NATIONAL CEDARCHEX CORPORATION, OF FULTON COUNTY, GEORGIA, A CORPORATION OF GEORGIA.

FUMIGATING DEVICE.

Application filed April 26, 1927. Serial No. 186,747.

Generically this invention relates to dispensing devices, but it more specially comprehends the type adaptable for disinfecting and fumigating purposes.

5 An important object of this invention is the provision of means for supporting the container of a fumigating substance, and effecting automatic discharge of the same therefrom.

10 A further object of this invention is the provision of a holder for a disinfecting or fumigating container insertable therein, and having detachable closure means adapted to engage at the neck of the container, and to 15 effect locking of the container in the holder, said closure adapted to permit automatic discharge of the fumigating contents to the surrounding atmosphere.

With these and other objects in view, which 20 will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a front elevation of my improved 25 fumigating device with container and closure in operative position;

Fig. 2 is a side elevation of Figure 1;

Fig. 3 is a top plan view of the closure showing perforations therein, and its supporting member; and

35 Fig. 4 is a central vertical section through a modified form of closure, showing the wick positioned therein.

The devices of this character with which I am familiar either require the initial emptying of the contents of the original container 40 therein, or owing to their construction, are too costly to produce and for other reasons unsatisfactory, and it was to overcome the deficiencies of such devices by providing a 45 device in which the original container is easily positioned and removed, and having a closure means for expeditiously locking the container in operative position, and so constructed as to permit evaporation or proper 50 discharge of the contents of the container

into the surrounding atmosphere, that I designed the device forming the subject matter of this invention.

In the illustrated embodiment characterizing this invention there is shown a holder 55 (A) adapted to support a container (B). The holder (A) is preferably constructed from cedar or similar aromatic woods adapted to blend with the fumigating substance, and comprises an upright base member (5) 60 having a laterally extending container supporting member (6) suitably secured to the lower end thereof. Suitably secured to the base member (5) at a point spaced from its upper end, as at 7, is a laterally extending member (8) 65 corresponding in configuration to the member 6 and in spaced parallelism therewith. The member 8 is formed with a central bore (9) adapted to receive the depending barrel portion (10) of the thimble-like closure or cap (C), the upper end of said portion 10 terminating in an integral top portion (11), said portion 11 being provided with a plurality of perforations or apertures 70 (12) for a purpose which will hereinafter 75 more fully appear. A perpendicular slot or recess (13) is formed in the inner wall of bore 9 to permit passage therethrough of the lug (14) formed integrally or otherwise on the portion 10 spaced from the lower end 80 thereof, said lug adapted to coact with the member 8 and when operatively positioned, to prevent disconnection of the closure (C) from said supporting member 8.

The modified form of closure (C') is 85 exactly similar to closure C except that in addition to the perforations (12) it is formed with spaced slots (15) through which is adapted to be threaded the upper end of a wick (16) for the purpose of aiding or regulating the evaporation of the contents of the container (B), as will be clearly understood without further explanation.

From the above description it is evident 95 that when the closure (C) is elevated or withdrawn from the bore (9), the container (B) may be placed on the support (6) and the closure (C) reinserted in the bore (9) and lowered to engage over the neck of the container (B). By a slight clockwise move- 100

ment of the closure (C), the lug (14) will be brought into engagement with the under surface of member 8 which will not only prevent disconnection of the closure from its support, but will securely lock the container in the device, and effect rigid association of the components A, B, and C. The device may then be placed where desired, either on a shelf or suspended by means of the opening (17) in base member 5, or by any suitable fastening means carried by said base being inserted over a hook, nail or the like.

From the above, it is evident that when the device has been suitably positioned, the volatile contents will be discharged into the surrounding atmosphere through apertures (12), or in conjunction with wick (16), as desired.

It will be noted that I have provided a device of the above character of ornamental design and pleasing appearance, simple in construction, manufacturable at a negligible cost, and efficient for the purposes intended.

Although in practice I have found that the form of my invention illustrated in the accompanying drawings and referred to in the above description, as the preferred embodiment, is the most efficient and practical; yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. A vaporizing device including a base member, a second member above and spaced from said base member, said second member having an opening therein, a container of vaporizable liquid having a neck, said container supported by said base member with the neck aligned with said opening and spaced from the sides thereof, a thimble like closure cap fitted over said neck, said closure cap being positioned in said opening, a lateral projection on said closure cap engaging said second member in such manner as to hold said cap securely on said neck, said cap being provided with means to effect vaporization of said liquid from said container into the surrounding atmosphere.

55. 2. A vaporizing device including a base member, a second member above and spaced from said base member, said second member having an opening therein, a container of vaporizable liquid having a neck, said container supported by said base member with the neck aligned with said opening and spaced from the sides thereof, a thimble like closure cap fitted over said neck, said closure cap being positioned in said opening, a lateral projection on said closure cap engaging said sec-

ond member in such manner as to hold said cap securely on said neck, said cap having a plurality of perforations therethrough communicating with said container and wick means passing through some of said perforations and extending into the liquid in said container, whereby vaporization of said liquid into the surrounding atmosphere is effected.
